S. CABOT

RADIO RECEIVING SYSTEM

Filed Nov. 19, 1924

UNITED STATES PATENT OFFICE.

SEWALL CABOT, OF BROOKLINE, MASSACHUSETTS.

RADIO RECEIVING SYSTEM.

Application filed November 19, 1924. Serial No. 750,794.

The present invention which is an improvement on the system described in my application Serial No. 734,205, filed August 26, 1924, relates to radio-receiving systems of the radio-frequency amplifier type in which a three-electrode vacuum tube is interposed between an oscillatory receiving circuit and a second oscillatory circuit, the said circuits not being exteriorly coupled or interlinked, but coupled or interlinked only by the elements of said tube. In systems of this type if capacity only is varied for tuning both circuits, any local oscillations that may be created in the system by controlling the second oscillatory circuit will be of greater intensity on short wave lengths, and if inductance only is varied, such local oscillations will be of greater intensity on long wave lengths. However, if the inductance of one circuit is kept constant and the capacity thereof only is varied, and the capacity of the other circuit is kept constant, or approximately constant, and the inductance thereof only is varied, such local oscillations, so created by such control, will be of substantially equal intensity for all wave lengths within the range of the system.

I have discovered that certain advantages result from connecting the ends of the input circuit of the amplifier tube to the receiving inductance, for example a receiving loop, at one of the terminals thereof and at a point intermediate said terminals, respectively, instead of connecting said input circuit to the terminals of said inductance, the exact location of said point intermediate the terminals of said inductance depending upon the electromagnetic and resistance constants of the several elements of the system and being best determined experimentally, although under certain conditions I have found that the best results are obtained when said point is approximately midway between the terminals of said inductance.

Some of the advantages obtained by connecting the filament of a three-electrode tube to one terminal of the receiving inductance or loop and the grid of said tube thereto at a point intermediate the terminals thereof, for instance, at a point midway between said terminals are (1) an increase in the selectivity of the system, (2) an increase in the wave-length range of the system for

a given condenser, (3) the obtaining of greater stability of adjustment to the "floating point" or the point at which the system is just on the verge of creating local oscillations, this being the condition in which the system is most sensitive to feeble electrical oscillations, and (4) the ability to reduce the intensity of any local oscillations that may be created in the system to zero or to as low a value as desired and at the same time provide a large amount of regeneration under control at all wave lengths within the tuning range.

The object of my invention is to provide a radio-receiving system whereby the advantages above enumerated may be realized in practice.

With the foregoing object in view my invention in its broadest aspect essentially consists in a receiving inductance and a vacuum tube having the ends of its input circuit connected thereto at one of the terminals thereof and at a point intermediate said terminals, respectively, such intermediate point being, under certain circumstances, approximately midway between said terminals.

My invention further consists in a fixed receiving inductance, such for example, as a loop, with a variable condenser connected across the terminals thereof, a vacuum tube having the ends of its input circuit connected, respectively, to one terminal of said inductance and a point intermediate said terminals in combination with a fixed condenser and a variable inductance associated with the plate circuit of said tube, and mechanical means for effecting the simultaneous variation of the capacity of said variable condenser and the value of said inductance, whereby any local oscillations that may be created in the system by changing the capacity of a third independent condenser (which may be in multiple with either of the condensers aforesaid), will be of approximately equal intensity for all wave lengths within the range of the system.

My invention consists also in a method of tuning radio-receiving systems of the radio-frequency amplifier type to the "floating point", or the point of maximum sensitivity for any wave length within the range of said system which consists, first, in simultaneously changing in opposite directions

the impedance of the input and output circuits of a vacuum tube as the wave length varies, for example, reducing the impedance of the input circuit by increasing the capacity thereof and increasing the impedance of the output circuit by increasing the inductance of said output circuit, whereby any local oscillations that may be created in said system by varying a separate adjustable controlling means, such as a condenser associated with either circuit, will be of substantially uniform intensity for any wave length within the range of said system; and, second, reducing the intensity of such local oscillations to zero or to as low a value as desired by an experimentally-determined fixed adjustment of the impedance of the input circuit.

In the drawing accompanying and forming a part of this specification the figure is a diagram of a radio-receiving system embodying my invention.

In the particular diagram selected for more fully disclosing my invention, 1 is a receiving inductance, shown in the present instance as a loop having fixed inductance, across the terminals 2, 3 of which is connected a variable condenser 4. The filament 5 of a three-electrode amplifying vacuum tube is connected to said loop at the terminal 3 thereof. The grid 6 of said tube is connected to said loop at the point 7 which is intermediate the terminals 2, 3 of said loop, said point 7 being best determined experimentally and its location depending upon the electromagnetic and resistance constants of the several elements of the system.

I have found that under certain conditions the point 7 may with advantage be approximately midway between the terminals 2, 3. A fixed condenser 8 and a variable inductance 9 which may be a transformer variometer of any suitable type, such for example, as a D-transformer variometer is associated with the circuit of the plate 10 of the three-electrode tube above mentioned.

The variable condenser 4 and variable inductance 9 are so arranged that their values may be simultaneously varied by any suitable single unitary means so constructed that for every position thereof the product of inductance by capacity in the input circuit of said tube shall be equal to the product of inductance by capacity in the output circuit thereof. In the present instance said condenser 4 and inductance 9 are shown as mounted on a shaft 11 rotatable by the knob 12. A second variable condenser 13, shown in the present instance as connected in multiple with the fixed condenser 8, although it may be connected across the terminals of the variable condenser 4, is employed to compensate for inequalities and ensure that for every position of the knob 12 the product of inductance by capacity in the input circuit

shall be equal to the product of inductance by capacity of the output circuit, to govern regeneration and the creation of local oscillations in the system, and to adjust the system to the "floating point" aforesaid.

By maintaining the inductance of the input circuit constant and varying only the capacity 4 thereof, and maintaining the capacity 8 associated with the circuit of the plate 10 constant or approximately constant, and varying only the inductance 9 of such plate circuit, any local oscillations that may be created in the system by varying the capacity of the condenser 13 will be of substantially equal intensity for all wave lengths within the range of the system, such intensity being controllable and reducible to zero or to as low a value as desired by experimentally selecting the location of the intermediate point 7 on the loop 1.

A suitable detector such as the tube 14 having a telephone receiver 15, or the like, in its plate circuit, is associated with the variable inductance 9 and condenser 10, although it will be understood of course that said tube 14 may be an amplifying tube or one of a series of amplifying tubes. The battery 16 is employed to heat the filaments of the two tubes and the battery 17 for supplying energy to the output circuits thereof.

Assuming that the point 7 is midway between the terminals 2, 3 of the receiving loop, the inductance of the grid circuit of the first tube is only approximately one-fourth of the inductance of the loop because in such case the grid or input circuit of said tube 6, 7, 3, 5, contains only one-half as many turns as the loop. Therefore the reactance of the variable condenser 4 on the grid circuit is only one-fourth as great as it would be if the grid were connected to the terminal of the loop 2, instead of the point 7 midway between the terminals 2, 3. It follows that a given change in the capacity of the condenser 4 will effect a larger proportional change in the apparent reactance between the grid 6 and filament 5 than if said grid were connected to said terminal 2. It is for this reason that the connection of said grid to the loop at the point 7 instead of to the terminal 2 of the loop greatly increases the selectivity of the system.

When the output circuit of the first tube is attuned to the frequency of the oscillations to be received and amplified, the grid-plate capacity is about ten times larger than its normal value, being equal to such normal value multiplied by $(\mu+1)$ where μ is the amplification factor. When the grid 6 is connected to the loop at the point 7, assumed to be midway between the loop terminals 2 and 3, the effect of the grid-plate capacity on the loop condenser 4 is only about one-fourth of that which would be exerted there-

on if said grid were connected to the loop at its terminal 2. It follows therefore that when the grid is connected to the loop at the point 7 the effective capacity of the loop is less for the zero setting of the variable condenser 4 than when the grid is connected to the terminal 2. For a condenser 4 of given capacity, the system can be made resonant to oscillations of higher frequency and shorter wave length by the mode of connection above described and therefore the wave length range of the system is increased.

The tube 5, 6, 10 will oscillate when its plate-circuit is attuned to a higher frequency than its grid circuit, and such oscillations may be stopped by increasing the capacity or the inductance of said plate circuit. The tube may be made to oscillate by reducing the frequency to which the grid circuit is attuned, and such oscillations may be stopped by increasing the frequency of said grid circuit. The apparent grid-to-plate capacity of the tube varies with the plate voltage, and as such voltage increases at resonance, it follows that the grid-plate capacity increases when the plate circuit is attuned to the frequency of the oscillations which are to be received and amplified. Such increase of grid-plate capacity is effective to increase the apparent capacity of the loop and thereby reduce the frequency to which it is attuned, thereby causing the tube to oscillate and creating a condition which is inherently unstable. However, by virtue of the connection of the grid to the loop at the point 7 instead of to the terminal 2, the effect of the grid-plate capacity on the loop condenser 4 is only one-fourth of the effect that would be produced if the grid were connected to the loop at the terminal 2 thereof. For this reason it is possible to obtain greater stability of adjustment to the floating point or the point at which the tube is just on the verge of oscillating.

The advantages above recited are quite independent of the adjustment of the electromagnetic constants whereby the regeneration may be governed to be of uniform intensity for all wave lengths within the range of the system, viz, the variation of the capacity 4, the inductance 1 remaining constant, and the variation of the inductance

9, the capacity of the condenser 8 remaining constant or substantially constant. 55

However the fourth advantage, viz, the ability to control, that is, minimize or suppress, the creation of oscillations in the loop circuit, is dependent upon obtaining regeneration of substantially equal intensity for 60 all wave lengths within the range of the system.

It will be obvious that when the system is designed as above set forth for such substantially equal intensity of regeneration, 65 the intensity of oscillations created in the system may be reduced to zero or to as low a value as desired, by reducing the impedance of the input circuit of the tube as by moving the point 7 closer to the terminal 3; and that such intensity may be increased by increasing the impedance of said input circuit as by moving the point 7 farther away from the terminal 3 and closer to the terminal 2. When the received energy is 70 small it is sometimes desirable to create feeble oscillations in the loop circuit 1, 4, by moving the point 7 closer to the terminal 2, and in the case of stronger waves, the intensity of such oscillations may with advantage be reduced to zero and the tendency to oscillate suppressed by moving said point 7 closer to the terminal 3. 75

Having thus described an illustrative embodiment of my invention without however 85 limiting the same thereto, what I claim and desire to secure by Letters Patent is:—

The method of tuning a radio-receiving system of the radio-frequency amplifier type to the point of greatest sensitiveness for 90 any wave length within the range of said system which consists, first, in simultaneously changing in opposite directions the impedance of the input and output circuits of a vacuum tube as wave length varies whereby any local oscillations that may be created in said system will be of substantially uniform intensity for any wave length within the range of said system, and, second, reducing the intensity of such local oscillations 95 to as low a value as desired. 100

In testimony whereof, I have hereunto subscribed my name this 17th day of November, 1924.
